UNITED STATES PATENT OFFICE

DONALD S. BARROWS, OF ROCHESTER, NEW YORK, ASSIGNOR, BY MESNE ASSIGNMENTS,
TO THE SYMINGTON COMPANY, A CORPORATION OF MARYLAND

JOURNAL BOX

Application filed October 30, 1924. Serial No. 746,795.

The invention relates to journal boxes and more particularly to the lid mechanism by which the journal box opening is closed, said lid being adapted to be pivotally connected to the journal box to permit access to the interior thereof.

The principal object of my invention, generally stated, is to provide a simple form of lid which may be readily, cheaply and advantageously formed of cast metal.

Another object of the invention is to provide a lid mechanism for journal boxes, the said lid having an imperforate portion completely enclosing the journal box opening so as to prevent the entry of dust, dirt or water into the box.

Still another object of the invention is to provide a journal box lid having an imperforate portion covering the journal box opening, said lid being provided exteriorly of the journal box with spring mechanism cooperating with the lid and box so as to firmly maintain the lid in either opened or closed position.

A still further object of the invention is to provide in a cast lid having an imperforate portion covering the journal box opening, a hooded portion enclosing the spring mechanism, said hooded portion also enclosing a portion of the hinge lug and serving to prevent the entry of dirt and moisture within the spring operated recess.

In the drawings:

Figure 1 is a view in front elevation of a portion of a lid constructed in accordance with my invention, a portion of the lid being broken away to more clearly illustrate the invention.

Figure 2 is a longitudinal vertical sectional view through the lid and journal box, only a portion of the latter being illustrated.

Figure 3 is a transverse sectional view of the lid taken on the line 3—3 of Figure 2, the direction of view being indicated by the arrows adjacent the ends of said section line.

Throughout the specification and drawings like parts are designated by like reference characters.

The numeral 1 designates a journal box of the A. R. A. construction having the usual

hinge lug 2 projecting upwardly from the roof 3 at a point adjacent the forward edge 4 of the journal box. The said hinge lug 2 is provided with an opening 5 for the reception of the hinge pintle 6 by which the lid 8 is pivotally connected to the journal box. The lug 2 is provided with angularly disposed bearing faces 7 and 7^a, as is customary, said faces being adapted to coact with a spring mechanism carried by the lid so as to maintain the lid in closed or open position.

The lid 8 is preferably formed as an integral casting either of cast steel or malleable iron and is provided with a lip 8^a at the top and sides, the said lid being adapted to overlie the wall 9 of the opening 10 of the journal box 1 to prevent the entry of moisture or dirt within the box. The lid may also be provided with interior flanges 11 and with a drip flange 12 so as to prevent the loss of the lubricating compound, the flanges 11 and 12 serving to reinforce and strengthen the lid.

At its upper end the lid is provided with a hood or pocket portion 13 which extends upwardly so as to partially enclose the lug 2. At opposite sides the hood portion is provided with ears 14 which are perforated, as at 15, so as to receive the hinge pintle 6 by which the lid 8 is pivotally connected to the journal box. The hood 13 is provided with an opening adjacent its lower edge 16, the purpose and object of which will be herein-after described.

Within the body of the lid and exteriorly of the journal box there is provided a curved depression or seat portion 17. At substantially the point where the depression 17 merges into the plane of the lid face, there is provided on opposite sides of the center, a pair of outwardly facing seats or lugs 18. On the interior face of the hood 13 at a point adjacent the lower end 16, there are provided bearing lugs 19 having curved bearing faces 20. In order to provide means for resiliently maintaining the lid in contact with the walls of the opening 10, when the lid is in closed position and also for maintaining the lid in open position, so as to permit of free access to the interior of the journal box, I provide a

torsion spring 21, said spring being provided with downwardly extending arms 22 each of which is adapted to seat upon one of the lugs or seats 18. Each of the arms 22 extends upwardly and merges into a coil 23 and extending 5 upwardly from the adjacent ends of the coils 23 are the arms 24 which may be and preferably are integrally connected so as to form an inverted U-shaped member 25, said member being conveniently provided with a wearing shoe 26 which may be connected to the arms 24 by means of bendable clips 27. The shoe 26 is, as will be seen from Figure 2, normally adapted to contact the face 7 of the lug 2 when the lid is in closed position. The 10 position of the parts, that is the bearing faces 18 and 20 and the recessed portion 17 is such that when the torsion spring 21 is forced upwardly within the opening between the hood 13 and the lid 8, the spring is placed under a 15 considerable initial tension, the said tension, together with the portions 28 of the lugs 18, serving to prevent the displacement of the 20 said spring.

25 It will be observed upon consideration of Figure 2, that the spring 21 reacts against the lug 2 at one end and against the bearing portions 18 at the opposite end and since the bearing portions 18 are substantially in a 30 central position with reference to the journal box opening, the pressure from the spring will be substantially centralized on the lid so as to force all faces of the lid into intimate contact with the walls of the journal box 35 opening. The flange 8^a is omitted along the outer face of the hinge lug 2, as shown in Figure 2, and in order to compensate for the loss of metal at this point, I preferably reinforce the wall of the lid adjacent the hinge 40 lug by providing an exterior boss 29 thereon.

A lid constructed in accordance with my invention provides a complete closure for the journal box opening and housing for the actuating spring, and the hood portion thereof overlying the hinge lug prevents the entry and accumulation of dirt along the face of the journal box forwardly of the hinge lug and at the same time acts as a water shed to prevent the entry of moisture to the interior 45 of the journal box at this portion. This last function is materially assisted by providing the flange 8^a completely surrounding the exposed portions of the walls of the journal box 50 opening.

55 Having now described my invention, what I claim is:

1. The combination with a journal box 60 having a pivot lug thereon, of a lid pivotally connected thereto, said lid having an imperforate portion completely closing the opening of said journal box, a hood integrally formed on said lid and adapted to partially enclose said pivot lug, said hood serving as pivot means for said lid, a torsion spring 65 housed within said hood and reacting at op-

posite ends against the lug and lid and a lug on said lid cooperating with said spring to prevent undesired displacement thereof.

2. The combination with a journal box 70 having an integral pivot lug thereon, of a lid for said box, said lid having an imperforate portion adapted to completely close the opening of said box and being further provided with a hood portion rigidly outstanding from a face of said lid, portions of said hood being adapted to embrace said lug, means extending through said portions of the hood and lug for pivotally connecting said lid to said journal box, and a torsion spring member housed within said hood, insertible therein from below, removably held therein by bearing portions and reacting at opposite ends against said lid and hinge lug. 75

80 3. A lid for journal boxes comprising an imperforate portion designed to contact the entire periphery of a journal box opening and provided with a pocket, formed rigidly on a face thereof, for housing an actuating torsion spring, said pocket being formed with bosses for engaging and properly placing said spring. 85

4. A lid for journal boxes comprising an imperforate portion designed to completely close a journal box opening, and a hood portion formed integral therewith on the outer face thereof and providing a downwardly opening pocket for a lid-actuating torsion spring, with intermediate coil portions, said hood portion being provided with bearing lugs for engaging said coil portions and means for pivotally connecting said lid to a journal box, said lid being formed with means adapted to removably engage and retain said spring in place. 100

105 5. A lid for journal boxes comprising a plate portion designed to completely close the opening in a journal box, a hood portion extending from the outer face of the plate portion and forming a torsion spring pocket between said plate portion and the hood portion, said hood portion being provided with bearing means adapted for engagement by a removably associated spring and extended to form perforated ears for cooperating with a journal box hinge lug to pivot said lid to said box. 110

115 In testimony whereof I affix my signature.
DONALD S. BARROWS.
